Term of patent 14 years

Int. Cl. D17—04

U.S. Cl. D56—1

FIG. 1.

FIG. 2.

FIG. 3.

FIG. 4.

FIG. 5.

FIG. 6.

FIGURE 1 is a perspective view of a drumhead tensioning lug for musical drums, showing my new design;

FIGURE 2 is a front elevational view;

FIGURE 3 is an end view, showing the upper end in FIGURE 2;

FIGURE 4 is a side elevational view, the opposite side being the mirror image thereof;

FIGURE 5 is a rear elevational view; and

FIGURE 6 is an opposite end elevational view thereof. The side not shown in FIGURE 4 is the mirror image of the side shown therein.

The broken line showing of a portion of a musical drum and a drumhead tensioning rod in FIG. 1 is for illustrative purposes only.

I claim:

The ornamental design for a drumhead tensioning lug for musical drums, substantially as shown and described.
